ATTORNEY.

UNITED STATES PATENT OFFICE

JOHN L. DRAKE, OF TOLEDO, OHIO, ASSIGNOR TO LIBBEY-OWENS GLASS COMPANY, OF TOLEDO, OHIO, A CORPORATION OF OHIO

WIDTH-MAINTAINING WHEEL

Application filed September 14, 1925. Serial No. 56,173.

The present invention relates to sheet glass apparatus, and has particular reference to an improved form of sheet width maintaining means.

5 In the Colburn Patent No. 1,248,809, granted December 4, 1917, a sheet of glass is continuously drawn in a vertical plane from a mass of molten glass, after which the sheet is deflected over a bending member, passed 10 over a draw table, and through an annealing oven or leer. To prevent the sheet from narrowing at its base in the Colburn process, a pair of rotatable knurled rolls are positioned at each edge of the sheet, one roll on each 15 side thereof. Although the knurled rolls are entirely satisfactory as far as holding the sheet to width is concerned, they are not entirely satisfactory because of the comparatively high waste caused by their use. This 20 waste consists of a thickened edge portion which is in the neighborhood of 6 or 7 inches in width, the thickened portion extending from the edge of the sheet inwardly toward the center. As the same amount of waste 25 takes place at both edges of the sheet, the usable net width of sheet is much less than the gross width of sheet originally drawn.

In the present invention it is an aim to provide means that will be satisfactory as 30 width maintaining means, while at the same time the amount of edge glass which must be removed when cutting the sheet into commercial sizes is considerably less than heretofore.

35 An important object is to provide a grooved wheel adapted for contact with the edge of the sheet for holding the same to width.

Another object is to provide a rotatable wheel having a groove at its periphery, the 40 edge of the sheet being drawn contacting with the wheel within the groove so that the sheet will be held to width, while at the same time a slight lateral tension will be exerted on the sheet at its base, thus overcoming the 45 tendency of the sheet to contract, which contraction causes slight surface defects in the said sheet.

Other objects and advantages of the invention will become apparent during the 50 course of the following description.

In the drawings wherein like numerals are employed to designate like parts throughout the same,

Fig. 1 is a fragmentary transverse section through one form of apparatus with 55 which this device may be used, illustrating the device in operation,

Fig. 2 is a transverse longitudinal section through one form of apparatus,

Fig. 3 is a similar view of a slightly modified form of construction,

Fig. 4 is an elevation of one of the wheels, and

Fig. 5 illustrates a form of cooler which 65 may be used in conjunction with the rotatable 65 wheel.

Although this invention is particularly well-adapted for use in connection with the Colburn machine above referred to, it is not necessarily limited to this specific construc- 70

75 Numeral 10 designates a draw-pot which, in the Colburn machine, is in open communication with a suitable tank furnace, by which means a mass of molten glass is continuously supplied thereto. The sheet 12 is continuously drawn from the mass of glass 11, the sheet supplying meniscus 13 being at the base of the sheet 12. A bending roll 14 is provided to deflect the sheet from one plane 80 to another.

85 My improved construction consists of a rotatable wheel or disc 15, rotatably supported upon the bracket 16 carried by a frame member 17. The wheel or disc 15 is provided in its periphery with the groove 18, adapted to contact with the edge 19 of the sheet 12. The wheel 15 carries a gear or pinion 20 adapted to mesh with a drive gear or pinion 21 by which means the wheel is positively 90 driven in a manner to feed the glass upwardly. The temperature of the wheel 15 is preferably so controlled that there will be a tendency for the glass to stick within the groove so that it will not pull away from the groove, and also to exert a lateral tension on the sheet near its base. The temperature of the disc, 95

which is preferably hollow, may be controlled by air which may be introduced through a pipe 22 and nozzle 23, or if desired through 100

means of a fluid 24. The sheet supplying meniscus 13 is much thicker than the sheet 12 so that sufficient glass is drawn into the groove 18 to form a beaded edge 25 or an edge 26 which is slightly different than the edge 25 because of the fact that the groove is relatively much deeper.

10 A scraper 27, carried by the troughed bracket 16 and having a shape approximately that of the groove within the periphery 18, is used to remove any particles of glass or dirt that may stick to the wheel after the glass has left the same.

15 Fig. 1 clearly shows the edge 28 of the sheet being offset from the edge 29, illustrating the effect of the lateral tension exerted by the wheel. A substantially U-shaped cooler 30 may be used to lower the temperature of the thickened beaded edge 25 on the sheet as soon as it leaves the rotatable wheel 15.

20 Although this invention is illustrated in connection with the well-known Colburn machine, it is by no means necessarily restricted to this particular machine.

25 It is to be understood that the form of the invention herewith shown and described is to be taken as the preferred embodiment of the same, and that various changes in the 30 shape, size and arrangement of parts may be resorted to without departing from the spirit of the invention or the scope of the subjoined claims.

35 It has been illustrated and described here-
40 in that the groove wheels are positively driven by a set of bevel gears. The positive drive may be eliminated and in that event the rotation thereof will be dependent upon the traction created by the adhesion thereto of the upward traveling sheet edges. In order that relative speeds may exist between the periphery of the wheel and the sheet drawing mechanism, the wheel may be provided with a brake. The temperature of the 45 members may be controlled by either cooling or heating them as the occasion so demands.

Claims:

1. In sheet glass apparatus, means for drawing a sheet from a mass of molten glass, 50 a grooved member engaging the border portions of the sheet, and a scraper disposed within the groove.

2. In sheet glass apparatus, means for drawing a sheet from a mass of molten glass, 55 a grooved member engaging the border portion of the sheet, a support for the grooved member having a trough therein adapted to receive particles removed from the said member, and a scraper attached to one end of 60 the trough.

3. In sheet glass apparatus, a width main-
taining device comprising a disc member 65 having a single groove in its periphery, means for mounting the disc so that its axis of rotation will be substantially at right

angles to the surfaces of the sheet being formed, said disc being so arranged that the molten glass going into the border portion of the sheet will be received within said groove, means for rotating the disc in a manner that the border portions of the sheet will be fed upwardly and outwardly from the main body portion thereof, and means for circulating a temperature control medium through the disc so that the disc can be maintained at a temperature where the glass will have a tendency to stick thereto.

4. In sheet glass apparatus, a width maintaining device comprising a disc member having a single groove in its periphery, 70 means for mounting the disc so that its axis of rotation will be substantially at right angles to the surfaces of the sheet being formed, said disc being so arranged that the molten glass going into the border portions of the sheet will be received within said groove, means for rotating the disc in a manner that the border portions of the sheet will be fed upwardly and outwardly from the main body portion thereof, means for circulating a temperature control medium through the disc so that the disc can be maintained at a temperature where the glass will have a tendency to stick thereto, and means for cleaning the groove in 75 the disc after the sheet edge leaves the same.

5. In sheet glass apparatus, a width maintaining device comprising a disc member having a single groove in its periphery, 80 means for mounting the disc so that its axis of rotation will be substantially at right angles to the surfaces of the sheet being formed, said disc being so arranged that the molten glass going into the border portions of the sheet will be received within said groove, means for rotating the disc in a manner that the border portions of the sheet will be fed upwardly and outwardly from the main body portion thereof, means for circulating a temperature control medium through the disc so that the disc can be maintained at a temperature where the glass will have a tendency to stick thereto, and a cooler surrounding the edge portion of the sheet and positioned above and immediately 85 adjacent the disc.

6. In sheet glass apparatus, a width main-
taining device comprising a disc having a single groove in its periphery, the disc being so formed that channels are provided for the 90 reception of a moving temperature control medium, means for mounting the disc so that its axis of rotation will be substantially at right angles to the surfaces of the sheet being formed, said disc being so arranged that the molten glass going into the border portions of the sheet will be received within said groove, means for rotating the disc in a manner that the border portions of the sheet will be moved upwardly and outwardly from the 95

main body portion thereof, and means for circulating a temperature control medium through the channels formed in said disc whereby to maintain the temperature thereof where the glass will have a tendency to stick thereto.

7. In sheet glass apparatus, a width maintaining device comprising a disc having a single groove in its periphery, the disc being so formed that channels are provided for the reception of a moving temperature control medium, means for mounting the disc so that its axis of rotation will be substantially at right angles to the surface of the sheet being formed, said disc being so arranged that the molten glass going into the border portions of the sheet will be received within said groove, means for rotating the disc in manner that the border portions of the sheet will be moved upwardly and outwardly from the main body portion thereof, means for circulating a temperature control medium through the channels formed in said disc whereby to maintain the temperature thereof where the glass will have a tendency to stick thereto, and heat absorbing means arranged above and closely adjacent the disc member whereby to absorb heat from the sheet edge as it issues from the groove in said disc.

8. In sheet glass apparatus, a receptacle including side walls and adapted to contain a mass of molten glass, means for drawing a sheet therefrom, a width maintaining device arranged at the base of the sheet at each edge thereof, each width maintaining device comprising a disc member mounted over one side wall of the receptacle, the disc having a single groove formed in its periphery, means for mounting the disc so that its axis of rotation will be substantially at right angles to the surfaces of the glass sheet being formed, means for rotating the discs in a manner that the glass going to make up the border portions of the sheet will be moved upwardly and outwardly from the body thereof, and means for circulating a temperature control medium through the disc whereby to control the temperature of the disc in a manner that the glass will have a tendency to stick thereto.

9. In sheet glass apparatus, a receptacle including side walls and adapted to contain a mass of molten glass, means for drawing a sheet therefrom, a width maintaining device arranged at the base of the sheet at each edge thereof, each width maintaining device comprising a disc member mounted over one side wall of the receptacle, the disc having a single groove formed in its periphery, means for mounting the disc so that its axis of rotation will be substantially at right angles to the surfaces of the glass sheet being formed, means for rotating the discs in a manner that the glass going to make up the border portions of the sheet will be moved

upwardly and outwardly from the body thereof, means for circulating a temperature control medium through the disc whereby to control the temperature of the disc in a manner that the glass will have a tendency to stick thereto, and means for cleaning the groove in the disc after the sheet edge leaves the same.

Signed at Toledo, in the county of Lucas and State of Ohio, this 10th day of September, 1925.
